UNITED STATES PATENT OFFICE.

ALFRED WILSON, OF HANDSWORTH, COUNTY OF STAFFORD, ENGLAND.

APPARATUS FOR MAKING GAS.

SPECIFICATION forming part of Letters Patent No. 292,082, dated January 15, 1884.

Application filed May 4, 1883. (No model.) Patented in England October 3, 1882, No. 4,697.

To all whom it may concern:

Be it known that I, ALFRED WILSON, a subject of the Queen of Great Britain and Ireland, residing at Handsworth, in the county 5 of Stafford, Kingdom of Great Britain and Ireland, have invented new and useful Improvements in Apparatus for Making Gas, (for which I have obtained a patent in Great Britain, No. 4,697, bearing date October 3, 10 1882,) of which the following is a specification.

This invention relates to improvements in gas-producers of the kind described in the specification of an application for Letters Patent of the United States of America filed by me the 4th day of May, 1883. In that specification is described the combination, in a gas-producer, of a central tuyere, a solid hearth, and means for automatically removing incom- 15 bustible refuse from the apparatus.

According to my present invention I combine with a central tuyere and means for imparting rotary motion thereto a curved bar or blade, extending at its outer end over the 20 wall of the solid hearth, so that when the tuyere is rotated said arm shall be carried round with it in such manner that as it travels it will raise refuse matter within the box formed by the solid hearth and its wall and 25 cause said refuse to pass over the wall.

The accompanying drawings show a gas-producer embodying my present improvements, Figure 1 being an elevation; Fig. 2, a vertical section; Fig. 3, a plan; and Fig. 4, a 30 sectional plan on line *a b*, Fig. 2, with the cone *m* removed.

a is the hopper, by which coal is fed into the producer. *b* is the solid hearth, with annular walls *b' b''*, forming an annular box or 40 chamber, through the center of which passes the tuyere *c*, which is supported and guided at *d* and *e*, and has fast upon it, below the hearth *b*, a worm-wheel, *f*, in gear with a worm, *g*, on a shaft, *h*, supported in bearings *i*, and 45 operated in any suitable manner, such as by a hand-wheel, *j*. The tuyere *c* is provided with a curtain or cap, *c'*, that dips into an annular vessel formed by the hearth and its walls. To this cap or curtain is secured a curved 50 arm, *k*, formed with a blade, *k'*, and extending outward and upward till it overlaps the wall

b', where the end of the blade *k* takes at *k'* a vertical or approximately vertical shape, so as when in motion to throw over the wall *b'* any matter carried up by the part *k'*.

55

When the producer requires cleaning, the man in attendance turns the hand-wheel *j*, the motion being transmitted to the tuyere *c* and arm *k* by means of the worm *g* and worm-wheel *f*; or this motion may be continuous 60 from an engine. The arm *k*, being curved as shown, as it revolves, pushes the ashes in the annular box or hearth *b* outward into the annular space between the wall *b'* and the cone *m*, and lifts them over the edge of the wall *b'*. 65 The cone *m* (which supports the fire-brick lining *n*) and the annular box or hearth are bolted to three columns, *o o o*, as shown.

p is the outlet for the gases generated within the producer.

70

The lower part of the tuyere *c* is contracted inside to form a throat for the steam-blast.

q is the steam-jet.

r r are holes, into which a bar is inserted when the fuel in the producer requires stirring up. These holes are stopped with plugs 75 when not in use.

I do not herein claim the solid hearth adapted to hold water to form a seal to prevent the escape of gas, nor the central tuyere, nor, 80 broadly, the means for rotating the tuyere, or the means for automatically cleaning the hearth of incombustible material, since these features form part of the subject-matter of another application filed by me May 4, 1883, and numbered 93,922; but 85

What I do claim is—

1. In a gas-producer, the combination, with a solid hearth, of a central tuyere, means for imparting rotary motion thereto, and a curved 90 arm or blade for automatically removing incombustible refuse from the apparatus, substantially as described.

2. In a gas-producer, the combination of a solid hearth, with walls forming an annular 95 box or chamber to receive incombustible refuse from the fuel, a central tuyere with curtain or cap overlapping the inner wall of said box or chamber, a curved arm or blade attached to said tuyere, means for imparting rotary movement thereto, and a conical case dipping into said box or chamber, so as, when the 100

latter is charged with liquid, to form a trap or seal for preventing escape of gas, substantially as described.

3. The improved gas-producer comprising the hopper *a*, solid hearth *b*, annular box or chamber *b'* *b''*, tuyere *c*, worm-wheel *f* and worm *g*, shaft *h*, hand-wheel *j*, curtain or cap *c'*, curved arm *k*, with blade *k'* *k''*, cone *m*, fire-brick lining *n*, columns *o*, outlet *p*, steam-jet

q, and holes *r* *r*, the whole constructed, combined, arranged, and operating substantially as described and illustrated.

ALFRED WILSON.
